US0D1067980S

(12) United States Design Patent (10) Patent No.: US D1,067,980 S
(45) Date of Patent: * Mar. 25, 2025

(54) GAMING MACHINE ISLAND

(71) Applicant: Aristocrat Technologies Australia Pty Limited, North Ryde (AU)

(72) Inventors: Scott Olive, Brookvale (AU); Talles Vito, Warriewood (AU); Matthew Deitz, Dee Why (AU)

(73) Assignee: Aristocrat Technologies Australia Pty Limited, North Ryde (AU)

() Term: 15 Years

(21) Appl. No.: 29/901,871

(22) Filed: Sep. 6, 2023

Related U.S. Application Data

(60) Continuation of application No. 29/856,023, filed on Oct. 10, 2022, now Pat. No. Des. 1,002,729, which is a division of application No. 29/827,938, filed on Feb. 23, 2022, now Pat. No. Des. 967,898, which is a division of application No. 29/735,520, filed on May 21, 2020, now Pat. No. Des. 954,829.

(57) CLAIM

The ornamental design for a gaming machine island, as shown and described.

DESCRIPTION

FIG. 1 is a front perspective view of a gaming machine island showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dashed broken lines in the figures illustrate portions of the gaming machine island that form no part of the claimed design.

1 Claim, 7 Drawing Sheets
